UNITED STATES PATENT OFFICE.

ALFRED S. McCASKEY, OF CHICAGO, ILLINOIS.

PRINTING-TELEGRAPH SYSTEM.

1,006,112.

Specification of Letters Patent. Patented Oct. 17, 1911.

Original application filed May 3, 1901, Serial No. 58,646. Divided and this application filed December 22, 1909. Serial No. 534,482.

To all whom it may concern:

Be it known that I, ALFRED S. McCASKEY, of Chicago, Illinois, have invented a new and useful Improvement in Printing-Teleg-
5 graph Systems, which invention is fully set forth in the following specification.

This invention has general reference to electrical signaling or communication, and relates more particularly to printing telegraph systems, and the present application is a division of my application Serial Number 58,646, filed May 3d, 1901.

The present invention relates to the receiving mechanism in a printing telegraph 5 or similar electrical signaling system.

Any suitable transmitting mechanism may be used with the receiving mechanism hereinafter described, but I preferably employ the transmitting mechanism constituting the 20 subject-matter of my said application Serial Number 58,646, filed May 3d, 1901.

The receiving mechanism embraces a suitable distributor, a selector and a printing device, the distributor distributing the 25 pulses to the selector wherein they are translated into a definite mechanical effect and which mechanical effect may operate a typewriter, type wheel or other device.

The selector consists of a plurality of 30 selecting elements which are controlled by a number of magnets equal to the number of permuted impulses transmitted over the line, and said selector magnets are controlled by two sets of magnets connected with the 35 distributor and selector magnets in such manner, that while a series of permuted impulses previously received by one set of said controlling magnets for the selector magnets is being transmitted to the selector magnets, a new series of permuted impulses is 40 being received by or set up on the other set of controlling magnets to be subsequently translated by the selector. The action of one set of controlling magnets with respect 45 to the selector magnets is independent of the action of the other set of controlling magnets. The distributor and controlling magnets for the selector magnets are operated by local circuits controlled by a polar- 50 ized relay, the magnets of which latter are included in the main line circuit, the arrangement being such that certain of the impulses 55 actuate only the distributor while others both operate the distributor and energize certain of the controlling magnets for the

selector magnets whereby such impulses so operating the distributor and energizing the selector magnet controlling magnets, close circuits to certain of the selector magnets and are therein translated to certain effects 60 which close the printing circuits. The latter impulses are termed the operating impulses.

The arrangement whereby two sets of magnets alternately control the selector magnets is advantageous by reason of the fact that an appreciable time is required to distribute a series of permuted impulses to one set of selector controlling magnets, while a much less time is required to transmit said 65 impulses from the selector controlling magnets to the selector, and there translate the same into a mechanical operation to effect printing. It will thus be seen that the selector and printing devices may be kept in 70 steady and uniform operation, receiving impulses alternately from the two sets of selector controlling magnets, and that thereby the speed of the receiving device is much increased over a single set of selector controlling magnets. If desired, more than two sets of selector controlling magnets may be 75 employed. Said selector may be mechanical or electrical and may be connected either 80 mechanically or electrically with a printing device in such manner that when a series of permuted electrical impulses are translated into a distinct effect, the printing device will be operated to print a character representing the particular permuted impulses 85 delivered to the selector. The main line at the receiving station enters a polarized relay thereat, which latter operates the local circuit which acts in connection with the distributing device to control the several operating 90 circuits in general to effect the offices and functions of the receiving device.

The polarized relay controls two principal operating circuits, one for operating an escapement mechanism which operates the 11 distributor step by step, and one for operating said escapement mechanism and for separately energizing the two sets of controlling magnets for the selector magnets, the arrangement being such that impulses 1 of one polarity will merely operate the escapement mechanism by which the distributor is advanced step by step, while impulses 1 of the other polarity will, in addition to operating said escapement mechanism and

the distributor, energize the controlling magnets for the selector magnets and set up a combination in the controlling magnets which is thereafter transmitted to the selector and translated into a distinct mechanical effect for producing the printing, as before stated.

The distributor consists mainly of a circular disk provided with two sets of segments, one set corresponding to each set of selector-magnet-controlling-magnets and each segment of each set being connected with one of the magnets of each set of selector-magnet-controlling-magnets. A rotary arm or switch lever passes over said segments, and said rotary arm is included in a circuit which includes the relay, the escapement magnet and the selector controlling magnet, so that when this circuit is closed, the current passes from said relay to the escapement magnet and actuates the escapement, and through the rotary arm of the distributor and the segments thereof and thence to the several selector-magnet-controlling-magnets connected with said segments from which it returns to the relay.

After a series of permuted impulses have been translated in the selector, and the printing of the character represented by the impulses effected, the controlling magnets are restored so as to be enabled to receive the next succeeding series of impulses to be transmitted thereto. The two sets of selector-magnet-controlling-magnets operate independently of each other and the restoration of one set has no effect upon the action of the other set.

In the drawings:—Figure 1 is a plan view of the distributor. Fig. 2 is a vertical section on the line 2—2 of Fig. 1. Fig. 3 is a top plan section on line 3—3 of Fig. 2. Fig. 4 is a side elevation of the distributor looking in the direction of the arrow on Fig. 3. Fig. 5 is a bottom plan section on the line 5—5 of Fig. 6 is a detail section on the line 6—6 of Fig. 4. Fig. 7 is a plan view of the selector. Figs. 8 and 9 are side and end elevations, respectively, thereof. Fig. 10 is a partial diagrammatic view of the selector plates. Fig. 11 is a diagram showing the selector and printing circuits. Fig. 12 is a partial plan view of the printing device. Fig. 13 is a side elevation thereof. Fig. 14 is a diagrammatic view showing the several circuits at the receiving station. Fig. 15 is a fragmentary detail of the distributor. Fig. 16 is a view showing the means for restoring the armatures of the selector-magnet-controlling-magnets.

The distributor which receives the current from the main line at the receiving station is illustrated in Figs. 1 to 6 and Figs. 14 and 15, and is provided with a vertical shaft I which is given a step-by-step movement by the magnet I¹, Fig. 14, through an

escapement comprising an escapement lever I² and ratchet I³ on the shaft. The shaft I tends to continuously rotate through the medium of clock or other suitable motor mechanism i², as indicated in Figs. 2 and 4. The shaft I carries a rotary switch arm I⁴ which travels over an annular set of ten segments i insulated from each other. Said arm I⁴ is also provided with a tail piece which travels in contact with two semi-circular plates i¹ which separately close the circuit to the selector magnets, as will hereinafter appear. Said shaft I also carries below the segments i a disk I⁶.

The selector L, which is illustrated in Figs. 7 to 10, consists of a frame supporting 31 series of plates L¹, each series being composed of six plates, between the adjoining ends of which are five breaks in the circuit. The plates of the 31 series are connected together at one end by a cross-bar L² and are separately connected at the other end to wires 15 leading to small printing magnets L³ which separately control a powerful printing magnet M. Mounted beneath the plates L¹ and extending parallel with each of the breaks between the plates referred to, is an insulating block or segment L⁴ each carried on a rock-shaft L⁵. The insulating blocks L⁴ carry in line with each of the plates L¹, metal plates l some of which close the breaks in one position of the blocks L⁴, while others close the breaks in the other position thereof. Said blocks are moved to one position by magnets, as hereinafter described, and are moved into their other positions by retracting springs. Said plates are so arranged that a permuted series of impulses closes all the breaks between one longitudinal series of plates and thereby establishes a path therethrough for the selector circuit. Keyed to one end of each of said rock shafts is a lever L⁶ carrying an armature l¹ at its lower end, said armature being attracted by one of the selector magnets L⁷ numbered from 1 to 5, three located on one side of the series of selector bars or elements and two on the other side thereof. The levers are retracted from the armatures by springs l².

The line wire 5 leads to the magnets of a polarized relay J, which is shown as made like the polarized relay illustrated and described in my prior U. S. Letters Patent, No. 498,289, granted to me on the 30th day of May 1893. One of the tongues of said relay is adapted for contact with a terminal j, and the other with a terminal j¹. Said polarized relay controls two circuits. One, when one of the tongues is in contact with the terminal j, closes a circuit to the escapement magnet I¹ through wires 6 and 7, and the other, when the other tongue is in contact with the terminal j¹, closes a circuit through one of two sets of magnets K, num-

bered from 1 to 5 inclusive, which control the selector magnets L^7 , said circuit embracing a wire 8 leading from the contact point j^1 , branch wires 9 leading to the magnets K , wires 10 leading from the magnets K to the segments i of the distributor, the rotary arm I^4 , a wire leading from said arm to the escapement magnet I^1 and from thence by wire 7 back to the relay. The magnets K control the selector magnets L^7 through a local circuit which is closed through the tail piece of the arm I^4 , the semi-circular plates i^1 of the distributor, and through the armatures of the magnets K . Said circuit includes wires 12 leading from said plates to the armature levers k at the magnets K , contact points k^1 with which the armature levers have contact when the magnets K are energized, wires 13 leading from said contact points to the selector magnets, and wire 14 leading from the selector magnets through the tail piece of the arm I^4 back to one of the plates i^1 .

The armature levers k of the magnets K which control the selector magnets normally rest against stationary back stops k^2 and when the armatures are attracted by their magnets, they are adapted to be locked in their attracted positions by means of spring-pressed locking levers k^3 . For this purpose each two armatures and levers are provided on their adjacent ends with roller contact pieces. When each armature k is in its normal position, against back stop k^2 , the center of the roller of said armature lever is located outside the center of the roller of the locking lever k^3 . When, however, the armature lever is moved to its attracted position, said roller of the armature lever is located inside of the center of the roller of the locking lever, the spring of the lever yielding to permit this movement and acting to lock said armature lever in its attracted position. Means are provided for restoring said armatures k to their normal positions after the printing has occurred, consisting of rock-shafts K^1 (Fig. 16) provided with rigid arms k^6 which pass inside the armatures and are adapted, when the shafts are rocked in one direction, to throw the armatures out away from the magnets, as shown in Fig. 16. The shafts K^1 are rocked and the arms k^6 swung to move the armature levers k away from their magnets by means of restoring magnets N , one for each set of magnets K . Said restoring magnets N are included in circuits which are closed immediately after the printing has occurred so as to restore the armatures of the selector magnet-controlling-magnets in order that another permutation of impulses may be set up thereon.

Before describing further the action of the restoring magnets and the means for energizing the same, I will refer briefly to the

printing device herein shown, and the action which the printing device has on the restoring magnet circuit.

It will be understood that the printing device may be either a printing type-wheel or an electric typewriter of common form. The latter device is herein shown and is so arranged that the single printing magnet M severally actuates all of the levers of the typewriter. The construction is shown in Figs. 12 and 13 and is made as follows: O^1 designate the printing levers of a typewriter, each having an upright arm O^1 pivoted at its lower end to said lever and normally retracted in one direction against a stop by a spring o . O^2 designates a frame which is pivoted on a shaft O^3 and carries the armature m of the printing magnet M . The magnets L^3 , connected by the wires 15 with the selector plates L^1 , are located in rear of the pivoted arms O^1 and each of said magnets, when energized, draws its arm under the front cross-bar of the frame O^2 . The printing magnet M is included in a local circuit embracing a battery 16, a wire 19 connecting one pole of the battery with the magnet, and the other pole with each of the arms O^1 . Said arms O^1 , when drawn under the frame O^2 by their magnets, have contact with a stationary metallic cross-bar O^4 , and said cross-bar is connected by a wire 20 with the magnet M . It will be seen therefore that when each arm O^1 is separately moved by its magnet into contact with the cross-bar O^4 , the circuit to the magnet M is closed, and the frame O^2 is depressed to make contact with said arm O^1 and actuates the particular type bar connected with said arm. The circuit through the selector is closed by means of a magnet P which, when energized, attracts one end of an armature lever P^1 and throws the other end thereof into contact with a terminal p . Said armature lever is connected by a wire 17 with the connecting plate L^2 of the selector and therethrough to any of a closed series of the selector plates. The magnets L^3 , connected with said selector plates, are all connected by a return wire 18 with the terminal p . Consequently, when the selector circuit is closed at p one of the magnets L^3 is energized and closes the printing circuit in the manner described, including the magnet M and wires 19 and 20 and effects the printing of a character as described. When the frame O^2 of the printing device is depressed, an arm o^1 rigid therewith is moved into contact with a terminal o^2 , and said arm and terminal are connected by wires 21 and 22 with a magnet Q , including a battery, whereby a circuit is closed to said magnet which energizes the magnet, retracts the armature P^1 from the terminal p^1 and opens the selector circuit. The magnet P is energized by a local circuit embracing wires 21 and 22.

and 22^a connected, respectively, with a terminal lever I⁸ and a yielding stop I⁹ located at the distributor. The terminal I⁸ is moved into contact with its yielding stop I⁹ and 5 the circuit to the magnet P closed by radial projections i² on the periphery of the disk I⁶ carried by shaft I, just after the outer end of the switch arm I⁴ has passed off one set of segments i, and after a time when a 10 permuted series of impulses has been transmitted to one of the sets of selector-magnet-controlling-magnets K. As said arm I⁴ passes off said set of segments, the tail piece of said arm passes onto one of the plates i¹ 15 which is in circuit with the armatures of the energized set of magnets K, as heretofore described, and thereby closes the selector magnets circuit through the selector magnets, thereby establishing a determinate path 20 through one of the series of collector plates, in the manner before described. Immediately after said path has been established, one of the projections i² moves the terminal lever I⁸ into contact with its yielding stop I⁹, and closes the selector-circuit-controlling-circuit through the magnet P, as heretofore described, thereby closing the selector circuit which closes the printing circuit, in 25 the manner described.

30 The restoring magnets N are controlled by magnets R which are included in local circuits embracing wires 24 leading to terminal levers I¹⁰ and wire 25 leading to yielding back stops I¹¹ with which said levers are 35 adapted to have contact. Said terminal levers I¹⁰ are moved into contact with their back stops I¹¹ by means of a semi-circular drop flange i³ on the disk I⁶, one of said circuits being closed during one half of the rotation of the disk, and the other closed during the other half of such rotation. Said restoring-magnet-controlling-magnets R, when 40 energized, attract armature levers r and move the same into contact with terminals 45 r¹. Said armature levers are locked in their attracted positions by means of spring-pressed locking levers r², these parts operating like the similar parts k, k¹ and k², before described. Each of said armature 50 levers r, when in contact with its terminal r¹, closes a local restoring magnet circuit, the two circuits including wires 26 and 27, the former leading to contact plates i⁸ on the terminal levers I¹⁰ and the latter to stationary back stops i⁵, respectively, for the 55 levers I¹⁰. A break occurs in the wire 26 at the terminal p¹ which is closed when the armature lever P¹ is in contact therewith, and which closing occurs immediately after 60 the printing is effected. While a permuted series of impulses are being set up on one set of the controlling magnets K for the selector magnets, as, for instance, the upper set, the terminal lever I¹⁰ included in the circuit 65 of the upper restoring-magnet-controlling-

magnet R is traveling on the drop flange i³ which closed the circuit to said upper controlling magnet R. The energizing of said upper controlling magnet R moves its armature lever into contact with its terminal r¹ 70 and closes the circuit at this point for the upper restoring magnet N. The circuit for said upper controlling magnet is open at the back stop i⁵, when the terminal lever I¹⁰ is moved away therefrom into contact with its yielding stop. Until the selector circuit controlling magnet P is energized, said restoring circuit is also closed at the terminal p¹. It will be seen, therefore, that each restoring magnet circuit must be closed at 80 three points in order to energize the restoring magnet, viz., at the terminal r¹, the terminal p¹ and the back stop i⁵. Just before the terminal lever I¹⁰ moves off the drop flange i³, and therefore permits the plate i⁹ to contact with the back stop i⁵, the magnet P is energized by contact of the terminal lever I⁶ with its yielding stop I⁹ so that the restoring magnet circuit is open at the terminal p¹ before it is closed at the back stop 90 i⁵. This operation prevents the energizing of the restoring magnet before the printing is effected. After the printing is effected, the armature lever P¹ is moved into contact with the terminal p¹ by the magnet Q, and 95 completely closes the restoring magnet circuit, thereby permitting restoration of the armatures of the upper set of magnets K. The action of the lower set of restoring-magnet-controlling-magnets is the same as 100 that above described, the lower controlling magnet R being energized at the time a combination is being set up on the lower magnets K. While a series of permuted impulses are being sent to the selector from one 105 set of magnets K, and are by the selector translated to effect the printing of a character represented by said impulses, a new combination is being set up on the other set of magnets K to be subsequently transmitted 110 to the selector.

The deenergizing of the controlling magnets R for the restoring magnets by the opening of the restoring-magnet-controlling-magnet circuit at the terminal levers I⁸ has 115 no effect on the restoring circuit for the reason that the armatures r thereof are held in their attracted positions by the locking levers r² and are held in such positions until restored by the magnets N. It will thus be 120 seen that the sets of selecting-magnet-controlling-magnets alternately control the selector magnets and that their action is entirely independent of each other, so far as any liability of confusion between the two 125 sets of controlling magnets arising is concerned. It may be observed, however, that should a certain selector magnet be energized by two successive permuted impulses, the bridging element l of the selector con- 130

trolled by that magnet will not be restored in the interim between the translation of one series of impulses and the reception of the next series by the selector magnets, but will be held in its operative position after the 5 translation of one set of impulses and the opening of the circuit to the set of controlling magnets which transmitted said impulses, by the immediate closing of the circuit to the other set of controlling magnets. The bridging elements not used in the translation of the subsequent series will, however, be promptly returned by their retracting springs and the closing of the circuit to the 10 other set of controlling magnets will have no effect thereon. This is due to the fact that the ring i^1 included in both of said circuits is composed of two insulated segments.

In order to produce synchronism between 20 the transmitting and receiving devices, I have introduced into the line wire 5 a regulating device made as follows: Said line wire is broken at a point near the distributor and a make and break in the circuit is 25 produced by the action of the distributor escapement lever. For this purpose the line wire is connected, at one side of the break with a swinging terminal lever V, which is normally held by a spring against a terminal V^1 to which the line at the other side of the break is connected. A tail piece on the escapement lever is adapted for contact with the terminal lever V and is insulated therefrom, the parts being so organized that 35 when the escapement lever is attracted to its actuating magnet it moves the terminal lever V from the terminal V^1 and produces a break in the main circuit. The escapement levers for the collector and distributor 40 are placed under the influence of springs in a manner to withdraw them from their actuating magnets, and to thereby complete the action of the escapement mechanism. In the event of the distributor shaft I stopping at 45 a point intermediate its normal position of rest, a restoring device is brought into operation which is shown in Figs. 4 6 and 14. The restoring device consists of two springs I^{14} I^{14} which, when the shaft is in 50 any of its proper positions of rest, bear upon insulation on said shaft but when the shaft is in an abnormal position, bear upon the shaft. These springs when in the latter position, close a local circuit to the magnet I^1 which operates the escapement mechanism of the distributor. The local circuit includes a sufficient resistance whereby a current from the local battery is less than that which passes through the magnet when 55 the operating circuit is closed at j or j' . The automatic restoring circuit, therefore, has no effect on the magnet I^1 during the normal operation of the distributor. Should the shaft, however, stop at an intermediate 60 point, the magnet I^1 will be energized by

the local automatic restoring circuit through the springs I^{14} to turn the shaft I to its proper position, after which rotation will continue through the main operating circuit. 70

What I claim is:—

1. In a telegraph system, wherein the characters are distinguished by permutations of a number of impulses of opposite polarity, the combination with the line and relay, of a distributor having a plurality of sets of distributing plates, each distributing the impulses representing a single character, and operating successively, whereby the impulses representing successive characters 80 will be distributed to the receiving apparatus through different circuits, and a receiving apparatus having sections corresponding in number to the sets of distributing plates, each section receiving the impulses of a single character from one of said sets of distributing plates. 85

2. In a telegraph system wherein the characters are distinguished by permutations of a number of impulses of opposite polarity, 90 the combination with the line and relay, of a distributor having two sets of distributing plates each receiving the impulses of a single character and operating successively whereby the impulses representing successive characters will be distributed to the receiving apparatus through different circuits, and one or more circuit controllers, operated by the distributor and controlling circuits to the receiving apparatus corresponding to 100 the two sets of distributing plates, such additional circuits being closed for one set of distributing plates, while the other set of distributing plates is in action. 95

3. In a printing telegraph system wherein 105 the characters are represented by permutations of impulses, the combination with the main line, of the selecting mechanism, two sets of controlling magnets therefor, and means for operating said sets in alternation. 110

4. In a printing telegraph system, and in combination with the main line, receiving mechanism comprising means for distributing the received impulses, and a selector receiving said impulses, said selector comprising 115 a number of sets of plates, each set having normally a number of interruptions, a series of circuit-closers adapted to close the circuits through said sets of plates, and means for operating said circuit closers 120 singly and in selected groups.

5. In a printing telegraph system, and in combination with the main line, receiving mechanism comprising means for distributing the received impulses, and a selector receiving 125 said impulses, said selector comprising a number of sets of conducting elements, each set having normally a number of interruptions equal to the number of permuted impulses transmitted over the line, a 130

- series of circuit closers adapted to close the circuits through said sets of conducting elements, and means for operating said circuit closers singly and in selected groups.
5. 3. In a printing telegraph system wherein the characters are represented by permutations of impulses, the combination with the main line, of the selecting mechanism, two sets of controlling magnets therefor, means 10 for operating said sets in alternation, and a restoring magnet for each of said two sets.
7. In a printing telegraph system wherein the characters are represented by permutations of impulses, the combination with the 15 main line, of the selecting mechanism, two sets of controlling magnets therefor, means for operating said sets in alternation, a restoring magnet for each of said two sets and a controlling magnet for each restoring 20 magnet.
8. In a printing telegraph system wherein the characters are represented by permutations of impulses, the combination with the main line, of the selecting mechanism, a plurality of sets of controlling magnets therefor, and means for operating said sets in alternation.
9. In a printing telegraph system wherein the characters are represented by permutations 30 of impulses, the combination with the main line, of the selecting mechanism, a plurality of sets of controlling magnets therefor, means for operating said sets in alternation, and a restoring magnet for each of said 35 sets of controlling magnets.
10. In a printing telegraph system wherein the characters are represented by permutations of impulses, the combination with the line and relay, of a distributor, a selecting 40 mechanism, a plurality of selecting magnets, and a plurality of controlling magnets for said selecting magnets.
11. In a printing telegraph system wherein the characters are represented by permutations 45 of impulses, the combination with the line and relay, of a distributor, a selecting mechanism, a plurality of selecting magnets, and a plurality of sets of controlling magnets the number of magnets in each set 50 being equal to the number of selecting magnets.
12. In a printing telegraph system, the combination with the main line, of a receiving mechanism comprising means for distributing the received impulses, a selector receiving said impulses, said selector comprising a number of sets of conducting members each set having normally a number 55 of interruptions, a series of circuit closers adapted to close the circuits through said sets of conducting members, and magnets for operating said circuit closers singly and in selected groups.
13. In a printing telegraph system, the combination with the main line, of a receiving 60
- 65
- ing mechanism comprising means for distributing the received impulses, a selector receiving said impulses, said selector comprising a number of sets of conducting members each set having normally a number of 70 interruptions, a series of circuit closers adapted to close the circuits through said sets of conducting members, magnets for operating said circuit closers singly and in selected groups, a plurality of sets of controlling magnets for said first-mentioned magnets, and means for operating said sets in alternation.
14. In a printing telegraph system, and in combination with the main line, receiving 80 mechanism comprising means for distributing the received impulses, and a selector receiving said impulses, said selector comprising a number of sets of conducting members, each set having normally a number of 85 interruptions, a series of pivoted circuit closers adapted to close the circuits through said sets of conducting members, and magnets for operating said circuit closers singly and in selected groups.
15. In a printing telegraph system, and in combination with the main line, receiving 90 mechanism comprising means for distributing the received impulses, and a selector receiving said impulses, said selector comprising a number of sets of conducting members, each set having normally a number of interruptions, a series of pivoted circuit closers adapted to close the circuits through said sets of conducting members, magnets for operating said circuit closers singly and in selected groups.
16. In a printing telegraph system, the combination with the main line, of a distributor which receives the impulses, a selecting mechanism to which the impulses are distributed, a plurality of sets of controlling magnets therefor, means for operating said sets in alternation, and a restoring magnet for each of said sets arranged in a local circuit which is adapted to be closed at the distributor.
17. In a printing telegraph system, the combination with the main line, of a distributor which receives the impulses, a selecting mechanism to which the impulses are distributed, a plurality of sets of controlling magnets therefor, means for operating said sets in alternation, a restoring magnet for each of said sets, and a controlling magnet for each of said restoring magnets arranged in a local circuit adapted to be 115 closed at the distributor.
18. In a printing telegraph system where- 120 in the characters are represented by permutations of impulses, the combination with the main line, of a distributor, a selecting 125
- 130

- mechanism, a plurality of sets of controlling magnets therefor arranged in a local circuit adapted to be closed at the distributor, and means for operating said sets in alternation.
- 5 19. In a printing telegraph system where-
in the characters are represented by permutations of impulses, the combination with the main line, of a distributor, a selecting mechanism, selector magnets associated therewith and arranged in a local circuit adapted to be closed at the distributor, a plurality of sets of controlling magnets for said selector magnets, and means for operating said sets in alternation.
- 10 20. In a printing telegraph system where-
in the characters are represented by permutations of impulses, the combination with the main line, of a distributor, a selecting mechanism, a plurality of sets of controlling magnets therefor, and means for operating said sets in alternation.
- 15 21. In a printing telegraph system where-
in the characters are represented by permutations of impulses, the combination with the main line, of a distributor, a selecting mechanism, printing means operated thereby by a plurality of sets of controlling magnets for said selecting mechanism, and means for operating said sets in alternation.
- 20 22. In a printing telegraph system, the combination with the main line, of a distributor, a selecting mechanism comprising a number of circuits, and a magnet in series with each circuit for effecting the printing of the character corresponding to the transmitted impulses.
- 25 23. In a printing telegraph system, the combination with the main line, of a distributor, a selecting mechanism comprising a number of circuits, a magnet in series with each circuit, and a single magnet arranged in a local circuit controlled by each of said other magnets, and means operated thereby for effecting the printing of the character corresponding to the transmitted impulses.
- 30 24. In a printing telegraph system, the combination with the main line, of a distributor, a selecting mechanism, a printing device associated therewith, a plurality of controlling magnets for said selecting mechanism, a restoring magnet for said controlling magnets arranged in a local circuit normally interrupted at a plurality of points, and means operated by the printing mechanism for closing the restoring circuit at one of said points.
- 35 25. In a printing telegraph system, the combination with the main line, of a distributor, a selecting mechanism, a printing device associated therewith, a plurality of sets of controlling magnets for said selecting mechanism, a restoring magnet for each set of controlling magnets arranged in a local circuit normally interrupted at a plurality of points, and means operated by the
- printing mechanism for closing the restoring circuit at one of said points.
26. In a printing telegraph system, the combination with the main line, of a polarized relay, an escapement movement associated therewith, and a make-and-break device for the circuit associated with said escapement movement to produce synchronism between the transmitting and receiving devices. 70
27. In a printing telegraph system, the combination with the main line, of a polarized relay, a magnet associated therewith, an armature for said magnet, and means operated thereby to make and break the main line circuit to produce synchronism between the transmitting and receiving devices. 75
28. In a printing telegraph system, the combination with the main line, of a polarized relay, a distributor, an escapement magnet associated with said polarized relay and associated with said distributor, an armature for said magnet, and means operated thereby to make and break the main line circuit to produce synchronism between the transmitting and receiving devices. 80
29. In a printing telegraph system, the combination with the main line, of a polarized relay, a distributor comprising a shaft and a rotating arm mounted thereon, a selecting mechanism to which impulses are delivered by said rotating arm, an escapement magnet associated with said relay and adapted to rotate said shaft, and means for energizing said magnet to rotate said shaft 90 when the latter stops at an intermediate point. 95
30. In a printing telegraph system, the combination with the main line, of a polarized relay, a distributor comprising a shaft and a rotating arm mounted thereon, a selecting mechanism to which impulses are delivered by said rotating arm, an escapement magnet associated with said relay and adapted to rotate said shaft, and a pair of arms acting to close a local circuit through said magnet to rotate said shaft when the latter stops at an intermediate point. 105
31. In a printing telegraph system, the combination with the main line, of a polarized relay, an escapement movement associated therewith, and a make-and-break device in the main line circuit and associated with said escapement movement to produce synchronism between the transmitting and receiving devices. 110
32. In a printing telegraph system, the combination with the main line, of a polarized relay, a magnet controlled by said relay, an armature for said magnet, and means operated thereby to make and break the main line circuit to produce synchronism between the transmitting and receiving devices. 115
33. In a printing telegraph system, the

- combination with the main line, of a polarized relay, a distributer, an escapement magnet controlled by said polarized relay and associated with said distributer, an armature 5 for said magnet, and means operated thereby to make and break the main line circuit to produce synchronism between the transmitting and receiving devices.
34. In a printing telegraph system, the 16 combination with the main line, of a polarized relay, a distributer comprising a shaft and a rotating arm mounted thereon, a selecting mechanism to which impulses are delivered by said rotating arm, an escapement 15 magnet controlled by said relay and adapted to rotate said shaft, and means for energizing said magnet to rotate said shaft when the latter stops at an intermediate point.

35. In a printing telegraph system, the combination with the main line, of a polarized relay, a distributer comprising a shaft and a rotating arm mounted thereon, a selecting mechanism to which impulses are delivered by said rotating arm, an escapement mechanism controlled by said relay and 20 adapted to rotate said shaft, and a pair of arms acting to close a local circuit through said magnet to rotate said shaft when the latter stops at an intermediate point.

In testimony whereof I have signed this 30 specification in the presence of two subscribing witnesses.

ALFRED S. McCASKEY.
